(57) **CLAIM**

I claim the ornamental design for a USB drive with hanger, as shown.

DESCRIPTION

FIG. 1 is a perspective view of the USB drive with hanger of the invention;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.
